UNITED STATES PATENT OFFICE.

HERMANN STÄUBLI, OF HOREN, SWITZERLAND.

SHEDDING MECHANISM FOR LOOMS.

SPECIFICATION forming part of Letters Patent No. 650,280, dated May 22, 1900.

Application filed October 15, 1896. Serial No. 608,995. (No model.)

To all whom it may concern:

Be it known that I, HERMANN STÄUBLI, a citizen of the Republic of Switzerland, and a resident of Horgen, in the Republic of Switzerland, have invented certain new and useful Improvements in Shedding Mechanisms for Looms, (for which I have obtained Letters Patent in Switzerland, dated July 3, 1896, No. 12,154; in Germany, dated July 23, 1896, No. 92,948; in France, dated July 20, 1896, No. 258,222; in Austria, dated October 26, 1896, No. 46/4,292; in Hungary, dated September 30, 1896, No. 7,210; in Spain, dated August 22, 1896, No. 19,550; in Italy, dated September 30, 1896, No. 42,361; in Belgium, dated August 17, 1896, No. 123,056, and in England, dated September 2, 1896, No. 19,355,) of which the following is a specification.

My invention relates to shedding mechanism, and particularly to that class of shedding mechanism actuated by lag-chains and known as "dobby mechanisms," and has for its object an arrangement of parts whereby the lag-cylinder can be driven from the weaving mechanism after each pick and will be equally effective if run in a positive or negative direction, at the same time adapted for "top," "bottom," or "center" shedding, and gives, above all, a uniform distribution of power.

Referring to the accompanying drawings, in which like letters and numerals of reference indicate like parts, Figure 1 is a side elevation of my machine. Fig. 2 is a part plan view showing the indicator-levers, lag-cylinder, and driving mechanism. Fig. 3 shows the driving mechanism for the lag-cylinder in side elevation. Fig. 4 shows the pawl and pinion for the lag-cylinder gear, and Figs. 5 and 6 are details showing the indicator-levers.

In Fig. 1, *a a* are the main or harness levers, (rear part only shown,) which carry the handles and are of usual form, their rear ends connected to the customary jacks *b*. At either end of the jacks *b* are the hooks *c c'*, each guided in a suitable grid *x x'* and engaging their respective reciprocating griffs *d d'* when in their lowered position. The griffs or knives *d d'*, each guided by and reciprocating in slots 50 in the frame of the machine, have perforations at either end to receive the hooked ends of the adjustable operating- rods *e* and *e'*.

These operating- rods *e e'* are threaded at their opposite ends and held in suitable bearings by nuts *e²*, which both secure the rod in position and admit of its longitudinal adjustment. The bearings for these rods are held at two ends of the usual three-armed operating-lever *f*, common to machines of this class and here driven independent from the mechanism for driving the lag-cylinder.

The lag-cylinder *G* and the operating-pinion are journaled in a detachable bracket *h'*, depending from the frame *z*. The cylinder *G*, operated by a driving-gear *h*, (here shown as having sixteen teeth,) carries the lag-chains *G*, of any suitable form, Fig. 1, and receives its intermittent motion through a pinion *l*, having one tooth, which may, if desired, be made integral with the sleeve of the bevel-gear *i'*, which drives it. Gearing with this bevel-wheel *i'* is a second bevel-gear *i* on the end of a counter-shaft *p*, journaled in a yoke-shaped bracket *q*, also detachably secured to the frame of the machine. This counter-shaft carries a sprocket-wheel *h'*, driven by a chain *k* from the weaving mechanism.

A lever *n*, fulcrumed at one end in the frame, carries the roller *m*, which serves as a pawl to lock the wheel *h'* in position after turning through one tooth to prevent any slip of the lag-cylinder due to unequal weight of the chains on either side, and at the opposite end of the lever *n* is a tension-spring *o*, secured at its lower end to a bracket *o'*, depending from the frame *z* and detachable therefrom. The roller *m* is lifted against the tension of the spring *o* and rolls over a tooth when the pinion *l* forces the wheel *h'* around the space of one tooth. This last-described mechanism for driving the lag-cylinder being held in detachable brackets can be changed from one side of the machine to the other, as floor-space and arrangement of the looms may require.

The indicator-levers *g g'* are all pivoted on a rod *g*, that extends from one side of the frame to the other and is held by nuts *g²*, screwed on the threaded ends projecting through the side framing. The indicator-levers *g g'* work in pairs, one of each, as *g'*, provided at its forward end with a hook or turned-up portion for engaging one of the

lower hooks c , while the other is shorter and has a straight end, on which rests the usual needle y , that lifts the upper hooks c' . Both the forward and rear ends of these indicator-levers are guided in grids x and x' , and their cam-faces are not, as is usual in such machines, at the same distance from their pivot-points g , but are at different distances therefrom, so that the pins or pegs on the lags of the lag-chain G' will lift one before the other. Consequently the knives or griffs must reciprocate relatively to the lifting of the hooks.

In Figs. 5 and 6 I have shown the cam-faces 1, 2 of the indicator-levers so constructed that they will fall after two revolutions of pinion l , or one-eighth of a revolution of the lag-cylinder, and the upper hooks c' will have fallen on their griff d' , and said griff will be on its return, through its lost motion, the distance 3, while the other griff is passing into position to receive the lower hooks when released by their tappet-levers.

The position of the cam-faces enables more uniform distribution of power, and consequently more even and uniform running of the machine, and decreases the jarring to a great extent, thus reducing the liability to over and under shedding while the loom is in operation.

It is obvious that the position of the cam-faces may be altered and the number of teeth

in the driving-gear h of the cylinder be changed to suit the requirements of the loom.

Having thus described my invention, what I claim as new therein, and desire to secure by Letters Patent, is—

The combination with the pattern-cylinder, mechanism controlled by the movements of the loom adapted to impart to said cylinder a step-by-step rotation in unison with said movements, the hooks and griffs; of a pattern or lag chain the lags of which are provided with pins or pegs and weighted indicator-levers actuated thereby, said levers arranged in pairs and provided with cam-surfaces displaced relatively to each other a distance equal to the travel of a pattern-chain pin during a partial rotation of the pattern-cylinder, whereby the upper and lower hooks actuated by a pair of levers are moved successively instead of simultaneously, into and out of engagement with their griffs by successive partial rotations of the pattern-cylinder, for the purpose set forth.

In testimony whereof I hereunto sign my name, in the presence of two subscribing witnesses, this 19th day of August, 1896.

HIERMANN STÄUBLI.
